LEWIS S. CHICHESTER, OF BROOKLYN, NEW YORK, ASSIGNOR TO HIMSELF,
G. H. NICHOLS, AND C. W. MILLS, OF SAME PLACE.

Letters Patent No. 74,893, dated February 25, 1868.

IMPROVEMENT IN GRAIN-DRIERS.

The Schedule referred to in these Letters Patent and making part of the same.

TO ALL WHOM IT MAY CONCERN:

Be it known that I, LEWIS S. CHICHESTER, of Brooklyn, in the county of Kings, and State of New York, have invented and made a certain new and useful Improvement in Grain-Driers; and I do hereby declare the following to be a full, clear, and exact description of the said invention, reference being had to the annexed drawing, making part of this specification, wherein—

Figure 1 is a vertical section of said grain-drier.

Figure 2 is a section through a portion of the grain-tables at right angles to fig. 1; and

Figure 3 is a plan of a portion of the grain-tables in one range.

Similar marks of reference denote the same parts.

The object of this invention is to facilitate the construction of grain-driers of various sizes and capacity, according to the use to which the drier is to be put, and at the same time direct the heat more or less upon the grain at particular stages in its descent, and maintain a pressure of the hot air upon it and beneath the supporting-tables.

In the drawing, *a* represents a vertical flue, into which the products of combustion from a bright open fire are conveyed, and mingled with a sufficient supply of atmosphere to bring the same to the proper temperature. The furnace should be provided with a separate flue and damper through which the smoke may pass in kindling the fire. I provide at one side of the flue *a*, a series of grain-supporting tables or hoppers, so formed as to allow the heated air to pass between the grain and the under side of the tables to convey away moisture to the escape-flue *b*.

A more detailed account of these grain-hoppers or tables is given hereafter, but the means for directing the air through between the tables and grain may be used with any character of tables.

In the vertical flue *a*, I place one or more deflecting-platforms *c*, leaving openings at *d*, next the range of tables or hoppers, and over these I attach the deflectors *e*, that are hung at their upper edge, and may be moved from the outside, so as to stand at any desired inclination, and, by taking the ascending heated air, deflect it through between the tables and grain; and according to the position of these deflecting-valves *e*, so the heat will be passed uniformly through in contact with the grain, or driven through more at one part than at another. The grain is supplied gradually at the upper part of the apparatus, and allowed to pass away gradually from a hopper at the bottom, and according to the capacity required for the apparatus, so it is to be made of a greater or less height, and the heated air in ascending, will, by each of the deflectors *e*, be directed in the required quantity through the grain-tables.

The grain-hoppers are made of metal; I prefer cast iron; and I form a section containing several inclined hoppers in each section, as seen at *g*. The opening at the bottom of each hopper allows the grain to pass down, and I so place the different sections that the openings of one hopper come over the apex or ridges between the inclined sides of the hoppers of the section next below. This arrangement causes the grain to pile at the under side of each hopper-opening in such a form that a free space is left over the grain and below the ridge between the inclined sides of the hoppers, as seen in fig. 1.

I prefer that these sections be made so that when turned end for end, the openings in one of the sections come on the line of the ridges in the contiguous section, as seen in the plan, fig. 3, so that the air-space under the ridges is zigzag, in order that the air may be detained in passing over the grain, and caused to impinge there-upon by the eddy and deflection of the current from a straight course, and thereby the air be rendered more efficient in drying the grain.

This character of grain-drier is capable of being made of a large or small capacity by simply increasing or lessening the number of the sections *g*, the casing containing the same being made accordingly.

Grain-driers made on this plan may be employed for drying grain immediately before grinding, or for preparing the same for storage, in bulk, directly from the field.

What I claim, and desire to secure by Letters Patent, is—

1. The vertical air-flue *a*, in combination with the deflectors *e*, platforms *c*, and grain-tables, platforms, or hoppers, substantially as and for the purposes set forth.
2. The sections *g*, having hopper-shaped openings, and placed together, substantially as and for the purposes set forth.

In witness whereof, I have hereunto set my signature, this fourteenth day of October, A. D. 1867.

Witnesses:

CHAS. H. SMITH,
GEO. D. WALKER.

LEWIS S. CHICHESTER.
